UNITED STATES PATENT OFFICE.

FREDERICK R. PARKER, OF CHICAGO, ILLINOIS.

TELEPHONE SYSTEM.

SPECIFICATION forming part of Letters Patent No. 767,953, dated August 16, 1904.

Application filed December 14, 1903. Serial No. 185,136. (No model.)

To all whom it may concern:

Be it known that I, FREDERICK R. PARKER, a citizen of the United States, residing at Chicago, in the county of Cook and State of Illinois, have invented new and useful Improvements in Telephone Systems, of which the following is a full, clear, concise, and exact description, reference being had to the accompanying drawing, forming a part of this specification.

My invention relates to a telephone system, my object being to provide improved means for operating the signaling devices in such a system.

It is customary in a telephone system to employ relays in the line-circuits thereof for operating the line-signals and relays in the plug-cord-connecting circuits for operating the supervisory signals. In this present invention I employ one relay in each line-circuit, the said relay being provided with a double armature and adapted to operate and control both the line-signal and the supervisory signal. Both armatures of the relay preferably operate the same contact-spring, although this is not essential. When both armatures are attracted to the core, the circuit of the line-signal is closed. When neither armature is attracted, the circuit of the supervisory signal is closed at the relay, and when one armature only is attracted neither of the said signaling-circuits is closed. I employ a winding in the cord-circuit, which shunts the said relay when connection is made with the line. The relay is preferably of a high resistance, and the said winding is preferably of a low resistance, thus allowing the said winding to shunt most of the current from the said relay when they are connected in multiple, as will be hereinafter shown. I preferably employ two superposed armatures at one end of the relay-core, but do not wish to confine this invention to such a particular arrangement of the said armatures. One limb of the calling-telephone line is connected through the said relay to a central source of electricity, and the other limb of the said line is preferably connected through an impedance-coil to the said source.

I will more particularly describe my in-

vention by reference to the accompanying drawing, illustrating same, in which is shown two subscribers' lines and the central-station signaling and connecting apparatus.

The line of subscriber A extends in two limbs *b* and *c* to the central station, where it terminates in suitable spring-jacks C C, limb *b* being connected to jack-contacts *d* *d* and limb *c* being connected to jack-contacts *f* *f*. Limb *b* is also connected through the winding of relay D to pole *r* of battery F. Likewise limb *c* is connected through the winding of impedance-coil E to pole *s* of battery F. Pole *r* of battery F is connected through conductor *t* to spring *i* of relay D. Spring *i* normally engages contact *j*, but is adapted to disengage contact *j* and to engage contact *h*. Contact *j* is connected through conductor *g* to jack-contacts *e* *e* of the several spring-jacks C C. Contact *h* is connected through conductor *n*, visual lamp *m*, and conductors *o* and *p* to pole *s* of battery F. Armature *l* of relay D is adapted to disengage spring *i* from contact *j* when it is attracted, and armature *k* is adapted to engage spring *i* with contact *h* when it is attracted. It is understood that when spring *i* engages contact *h* it is disengaged from contact *j*.

The line of subscriber B (shown upon the right of the drawing) is similar to the line of subscriber A, just described, and like characters are employed for indicating like parts.

In the plug-cord-connecting circuit the tip-contact of connecting-plug G is connected, through tip-strand *a*², condenser *g*², contact *k*², spring *j*², conductor *v*², contact *r*², spring *q*², and tip-strand *d*², to the tip-contact of connecting-plug H. The sleeve-contact of connecting-plug G is connected, through sleeve-strand *c*², condenser *h*², spring *n*², contact *m*², conductor *u*², contact *s*², spring *i*², and sleeve-strand *f*², to the sleeve-contact of connecting-plug H. The third conductor *b*² of connecting-plug G is connected, through visual lamp *u* and conductors *w* and *p*, to pole *s* of battery F. The third conductor *e*² of connecting-plug H is connected, through visual lamp *v* and conductors *x* and *p*, to pole *s* of battery F. The tip-strand *a*² of the plug-cord talking-circuit is connected, through conduc-

tor α^2 , the winding of impedance-coil I, and conductor t , to pole r of battery F. Contact h^2 of the plug-cord talking-circuit, separated from the tip-strand α^2 by condenser g^2 , is connected, through conductor y^2 , the winding of impedance-coil J, and conductor t , to pole r of battery F. When listening-key K is depressed, springs j^2 and n^2 thereof are disengaged from contacts h^2 and m^2 , respectively, and engaged with contacts i^2 and o^2 , respectively. Spring l^2 also engages contact h^2 . The operator's set (not shown in the drawing) is adapted to be bridged from spring l^2 to contact o^2 . Contact i^2 is for a busy-test circuit. When ringing-key L is depressed, springs q^2 and t^2 thereof are disengaged from contacts r^2 and s^2 , respectively, and engaged with contacts p^2 and u^2 , respectively. Contacts p^2 and u^2 are adapted to be connected to a source of calling-current. The insulating pin z of listening-key K is secured to springs j^2 and l^2 , so as to compel spring l^2 to operate with spring j^2 .

If subscriber A desires to talk with subscriber B, he lifts his telephone-receiver from the switch-hook, thereby closing the circuit between limbs b and c of his telephone-line in a manner well understood and allowing current from battery F to flow through the winding of relay D, limb b , substation A, limb c , impedance-coil E, and conductor p . This current traversing the winding of relay D energizes the core thereof and attracts both armatures l and k thereto. Armature l being attracted disengages spring i from contact j , and armature k being attracted engages spring i with contact h . Thus the circuit of battery F is closed through conductor t , spring i , contact h , conductor n , visual lamp m , and conductors o and p , thereby lighting the visual lamp m , which conveys to the operator the signal for connection. The operator then inserts the answering-plug G into a spring-jack C of line A. The insertion of the said plug into the said jack closes the circuit of battery F through conductor t , impedance-coil I, conductor α^2 , tip-strand α^2 , jack-contact d , limb b of the telephone-line, substation A, limb c , impedance-coil E, and conductor p . It will be readily seen that impedance-coil I forms a shunt around relay D, and as the resistance of relay D is high compared to the resistance of impedance-coil I the impedance-coil I takes the greater part of the current away from relay D. Relay D is still energized sufficiently to attract armature l , but not sufficiently to attract armature k . Thus armature k falls back to its normal position, and in so doing disengages spring i from contact h , thereby breaking the circuit through visual lamp m and extinguishing its signal. Spring i does not engage contact j , as it is held therefrom by armature l . The operator then depresses the listening-key K, and in so doing bridges her telephone set across

the metallic talking-circuit of answering-plug G and connects a terminal of the calling-plug H in circuit with a suitable busy-test arrangement. Upon learning that subscriber B is the subscriber called for and assuming that the line of subscriber B is not in use the operator inserts the calling-plug H into a spring-jack C of line B. The insertion of plug H into a jack C of line B closes the circuit of battery F through conductors p and x , visual lamp v , conductor α^2 , jack-contact e of line B, conductor g , contact j , spring i , and conductor t , thereby lighting the visual lamp v , which shows to the operator that subscriber B has his telephone-receiver on the switch-hook. The operator then depresses the ringing-key L in the usual manner, and thereby signals subscriber B in a manner well understood. In depressing the ringing-key L the operator also restores the listening-key K to its normal position. When subscriber B responds to the call and lifts his telephone-receiver from the switch-hook, he closes the circuit between the limbs of his telephone-line in a manner well understood, and thus closes the circuit of battery F through conductor p , impedance-coil E, limb c of his telephone-line, substation B, and limb b , where the circuit divides and takes two paths back to pole r of battery F, one said path being through the winding of relay D, the other said path being through jack-contact d , tip-strand α^2 , spring q^2 , contact r^2 , conductor v^2 , spring j^2 , contact h^2 , conductor y^2 , impedance-coil J, and conductor t . It will be readily seen that impedance-coil J forms a shunt around relay D, and as the resistance of relay D is high compared with the resistance of impedance-coil J the impedance-coil J takes the greater part of the current flowing through substation B. Relay D is sufficiently energized, however, to attract armature l to the core thereof, and thus disengage spring i from contact j ; but it is not sufficiently energized to attract armature k thereof. As spring i is disengaged from contact j the circuit through visual lamp v is thereby broken and the said lamp v is extinguished. The subscribers A and B are now connected for conversation with each other. When the conversation is completed and subscriber A hangs his receiver on the switch-hook he breaks the circuit between the limbs b and c of his line at the switch-hook in a manner well understood, and thereby stops the flow of current from battery F through relay D of line A. Relay D is thus deenergized, and armature l thereof falls away from the core, thereby engaging spring i with contact j . The engagement of spring i with contact j closes the circuit of battery F through conductor t , spring i , contact j , conductor g , jack-contact e , conductor α^2 , visual lamp u , and conductors w and p , and lights the visual lamp u , thus conveying to the operator the signal for disconnection. When subscriber

B hangs his telephone - receiver upon the switch-hook, he breaks the circuit of battery F through relay D of line B at his substation, as just described, for subscriber A. This causes armature *l* of relay D, belonging to the line of subscriber B, to fall away from the core thereof, and thus cause spring *i* to engage contact *j*. The engagement of spring *i* with contact *j* closes the circuit of battery F through conductor *t*, spring *i*, contact *j*, conductor *g*, jack-contact *e* of a spring-jack belonging to line B, strand *e*, visual lamp *v*, and conductors *x* and *p*, and lights the visual lamp *v*, thus conveying to the operator the signal for disconnection. When the operator receives both disconnect signals from subscribers A and B, respectively, she withdraws the connecting-plugs G and H from their respective spring-jacks, thereby breaking the circuits through the visual lamps *u* and *v*, respectively, and thus extinguishing their signals. All circuits and apparatus are now in their normal condition.

While I have shown visual lamps for the signaling devices throughout this invention, I wish it to be understood that any electrically-operable signaling device may be used in place of a visual lamp.

While I have illustrated this invention in connection with particular types of spring-jacks, connecting-plugs, keys, impedance-coils, &c., I do not wish to confine myself to such particular apparatus. Neither do I wish to limit this invention to a particular operator's equipment or busy-test arrangement.

The relay D, which I preferably employ, is provided with a pair of superposed armatures at one end thereof, but this arrangement of the armatures is not essential. This double-armature relay I have shown, described, and claimed in a copending application for patent on relay, Serial No. 194,392, filed February 19, 1904.

Having thus described my invention, what I claim as new, and desire to secure by Letters Patent, is—

1. The combination with a telephone-line, of a source of electricity, a double-armature relay connected from one limb of the line to the said source, an impedance-coil connected from the other limb of the line to the said source, a signaling device adapted to be operated by the said relay, a second signaling device placed under control of the said relay when connection is made with the line, means whereby the circuit of the said source is closed through the said relay and impedance-coil, thus operating both armatures of the said relay, and means for shunting the said relay when connection is made with the said line, and thereby releasing one armature of the said relay, substantially as described.

2. The combination with a telephone-line, of a source of electricity, a double-armature relay connected from one limb of the line to the

said source, each armature of the relay being adapted to control a local circuit, means for closing the circuit of the said source through the said relay and a limb of the telephone-line, with a suitable return, thereby operating both armatures of the relay, and means whereby the said relay is shunted by a resistance, thus rendering one armature only thereof, inoperative, substantially as described.

3. The combination with a telephone-line, of a source of electricity, a double-armature relay connected from one limb of the line to the said source, an impedance-coil connected from the other limb of the line to the said source, a local circuit for each armature of the relay and controlled thereby, a plug-cord circuit adapted to be connected with the telephone-line, an impedance-coil through which the said source of electricity is connected to a strand of the plug-cord-connecting circuit, a line-signal and a source of electricity in one said local circuit, a supervisory signal and a source of electricity adapted to be connected in the other said local circuit when connection is made with the telephone-line, means for closing the circuit of the first-mentioned source through the said relay and a limb of the telephone-line, with a suitable return, thereby actuating both armatures of the said relay and operating the line-signal, means whereby the cord-circuit impedance-coil is connected as a shunt around the said relay, when connection is made with the line, thereby rendering one of the said armatures inactive and extinguishing the line-signal, and means for opening the circuit of the telephone-line when connection is made therewith and thereby rendering both armatures of the relay inactive and operating the supervisory signal, substantially as described.

4. The combination with a telephone-line, of a source of electricity, a relay connected from one limb of the line to the said source, an impedance-coil connected from the other limb of the line to the said source, a pair of superposed armatures for the said relay, a spring adapted to be operated by either of the said armatures and thereby control two local circuits, one for each armature, a signaling device for each local circuit, means for closing the circuit of the said source through the relay and a limb of the telephone-line, with a suitable return, thereby actuating both armatures thereof, and means for shunting the said relay and thereby releasing one armature only thereof, substantially as described.

5. The combination with a telephone-line, of a source of electricity, a relay connected from one limb of the line to the said source, an impedance-coil connected from the other limb of the line to the said source, a pair of superposed armatures for the said relay, a spring adapted to be operated by either of the said armatures and thereby control two signaling-circuits, one for each armature, a plug-cord

- circuit adapted to be conductively connected with the said line, an impedance-coil through which the said source is connected to a main strand of the plug-cord circuit, a line-
5 signal for one said signaling-circuit, a supervisory signal in circuit with a strand of a connecting-cord and adapted to be connected in the other said signaling-circuit, when connection is made with the line, and means for operating the said armatures separately or together, for the purpose of operating and controlling the line-signal and supervisory signal, substantially as described. 70
6. In a telephone system, the combination with telephone-lines extending to a central station and terminating in suitable connection-
15 terminals, of a common source of electricity, a double-armature relay for each line and connected from a limb thereof to the said common source, a signaling-circuit for each armature of each relay and controlled thereby, a cord-circuit terminating in connecting-plugs and adapted to be connected with the said lines, an impedance-coil for each connecting-
20 plug and connected from the said source to conductors of their respective plugs, a third conductor for each plug and connected with respective supervisory signals, means for closing circuits of the said source through the
25 said relays, respectively, and thereby operating their armatures, means for shunting the said relays by the said cord-circuit impedances, respectively, when the cord-circuit is connected with the said lines, and means
30 whereby the supervisory signals are connected in their respective signaling-circuits when connection is made between the cord-circuit and the said lines, substantially as described. 80
7. In a telephone system, the combination with telephone-lines extending to a central station, of a common source of electricity, a relay for each line and connected thereto and to the common source, a pair of superposed armatures for each relay, a line signaling-circuit for each line, a supervisory signaling-circuit for each line and adapted to be completed when connection is made with the said lines, respectively, the said line signaling-circuits and supervisory signaling-circuits being
45 operated by respective armatures of the said relays, a plug-cord circuit adapted to be connected with the said lines, an impedance for each connecting-plug and connected thereto and to the common source, means whereby
50 the said impedances form shunts around the said relays, respectively, when connection is made with the said lines, and means for operating the said relays and signals, for the purpose of connecting and disconnecting sub-
55 scribers' lines, substantially as described. 85
8. The combination with a telephone-line, of a source of electricity, a double-armature relay connected from the line to the source, a circuit-controlling means adapted to be op-
60 erated by the armatures, signaling devices
65 adapted to be operated by the circuit-controlling means, and means for operating the relay-armatures separately or together and thereby operating the signaling devices. 90
9. A double-armature relay associated with a telephone-line, a circuit-controlling means adapted to be operated by the armatures, circuits to be opened and closed by the circuit-controlling means, and means for operating the relay-armatures separately or together. 75
10. The combination with a telephone-line, of a relay connected thereto, armatures for the said relay, a source of electricity, a signaling-circuit for each armature, a circuit-controlling means adapted to control the signaling-circuits and adapted to be operated by either armature, and means for operating the said armatures from the said source, separately or together, and thereby controlling the said signaling-circuits, substantially as described. 85
11. The combination with a telephone-line, of a relay normally connected thereto, the said relay being provided with two armatures, a source of electricity, a signaling-circuit adapted to be controlled by one armature, a plug-cord-connecting circuit for the line, a second signaling-circuit adapted to be completed when connection is made with the line, and placed under control of the other armature, and means for operating the relay-armatures from the said source, separately or together, substantially as described. 90
12. The combination with a metallic telephone-line, of a double-armature relay connected from one limb of the line to a source of electricity, an impedance-coil connected from the other limb of the line to the said source, a member adapted to be operated by both relay-armatures and thereby control two signaling-circuits, a connecting-circuit for the line, means for completing one of the said signaling-circuits when connection is made with the line, means for closing the circuit of the source through the relay and thereby operating the armatures thereof, and means for shunting the relay with the connecting-circuit, when connection is made with the line, and thereby rendering one armature only, of the relay, inoperative, substantially as described. 100
13. In combination, an electrical transmitting-line, an electrically-operable device associated therewith, circuit-controlling means, circuits to be controlled by said means, operable members for said device and adapted to operate said means, one operable member continuing the operation of said means from where another operable member left off, and means for operating said operable members one at a time or together. 110
14. A relay provided with two armatures and connected in circuit with a normally open telephone-line, respective signaling-circuits to be controlled by the said armatures, a source of electricity, the relay-armatures being adapted to operate on different strengths of 115
15. The combination with a telephone-line, of a relay connected thereto, armatures for the said relay, a source of electricity, a signaling-circuit for each armature, a circuit-controlling means adapted to control the signaling-circuits and adapted to be operated by either armature, and means for operating the said armatures from the said source, separately or together, and thereby controlling the said signaling-circuits, substantially as described. 120
16. The combination with a telephone-line, of a relay connected thereto, armatures for the said relay, a source of electricity, a signaling-circuit for each armature, a circuit-controlling means adapted to control the signaling-circuits and adapted to be operated by either armature, and means for operating the said armatures from the said source, separately or together, and thereby controlling the said signaling-circuits, substantially as described. 125
17. The combination with a telephone-line, of a relay connected thereto, armatures for the said relay, a source of electricity, a signaling-circuit for each armature, a circuit-controlling means adapted to control the signaling-circuits and adapted to be operated by either armature, and means for operating the said armatures from the said source, separately or together, and thereby controlling the said signaling-circuits, substantially as described. 130

current, respectively, in the relay - winding, and means for varying the strength of current from the said source through the relay - winding, during the use of the telephone-line, 5 and thereby operating the said relay-armatures, substantially as described.

15. The combination with a telephone-line, of a relay provided with two armatures and connected with the said line, a spring contact member adapted to be operated by either armature, two signaling-circuits controlled by the spring contact member, one signaling-circuit being open while the other is closed, and means for operating the said armatures from 15 a source of electricity, one at a time or both together, substantially as described.

16. A relay provided with a pair of superposed armatures and connected with a telephone-line, a line-signal and a supervisory 20 signal adapted to be operated by the said armatures, one of the said signals being put in condition for operation when connection is made with the line, and means for operating the said armatures separately or together, to 25 control the said signals.

17. A relay provided with a pair of superposed armatures and connected with a telephone-line, a spring member adapted to be operated by either of the said armatures, signaling-circuits adapted to be controlled by 30 the said spring member, and means for operating the relay-armatures, independently or together, during the use of the telephone-line, and thereby operating the signaling-circuits, substantially as described.

18. The combination with a telephone-line, of a relay provided with a pair of superposed armatures and connected with the line, a spring member adapted to be operated by either of 40 the said armatures, two signaling-circuits adapted to be controlled by the said spring member, a plug-cord circuit adapted to be connected with the said line, one said signaling-circuit being completed through a strand of 45 the plug-cord circuit when connection is made with the line, a source of electricity, means for closing the circuit of the said source through the said relay and telephone-line, and thereby operating the said armatures, and 50 means whereby the plug-cord circuit shunts the said relay, when connection is made with the line, and thereby releases one armature only and renders it inoperative, substantially as described.

55. 19. The combination with a telephone-line, of an electrically-operable device normally associated therewith at a central station and provided with operable members for controlling signals, signals adapted to be operated, 60 one being connected for operation when connection is made with the line, and means for operating the operable members separately or together.

20. The combination with a telephone-line, 65 of an electromagnet normally associated there-

with at the central station and provided with operable members adapted to control signal-circuits, signal-circuits adapted to be controlled by the operable members, one being completed when connection is made with the 70 line, and means for operating the operable members separately or together.

21. The combination with an electrical transmitting-line, of an electrically-operable device associated therewith and provided with 75 operable members, a line-signal and a supervisory signal adapted to be operated by the said operable members, one of the said signals being put in condition for operation when connection is made with the line, and means for 80 operating the said operable members separately or together, to control the said signals.

22. The combination with a telephone-line, of a relay associated therewith and provided with armatures, a circuit-controlling means 85 adapted to be operated by either armature, suitable circuits to be controlled by the circuit-controlling means, and means for operating the armatures separately or together.

23. The combination with a telephone-line, 90 of an electrically-operable device associated therewith and provided with operable members, a circuit-controlling means adapted to be operated by the operable members, suitable circuits to be controlled by the circuit-controlling means, and means for operating the operable members separately or together.

24. The combination with a telephone-line, of a double-armature relay associated with the line, a spring-switch adapted to be operated by either armature of the relay, suitable 100 circuits to be controlled by the spring-switch, and means for operating the armatures separately or together.

25. The combination with an electrical transmitting-line, of an electrically-operable device associated therewith and provided with 105 operable members, a circuit-controlling means adapted to be operated by the operable members, suitable circuits to be controlled by the 110 circuit-controlling means, and means for operating the operable members separately or together.

26. The combination with electrical transmitting-lines, of an electrically-operable device for each line and associated therewith, each said device being provided with operable members, a circuit-controlling means for each device and adapted to be operated by each operable member thereof, suitable circuits for 115 each circuit-controlling means and controlled thereby, a connecting-circuit for the lines, one circuit for each circuit-controlling means being completed when the said connecting-circuit is connected with the lines, and means 120 for operating the operable members of each device, separately or together.

27. The combination with an electrical transmitting-line, of an electrically-operable device associated therewith and provided with 125

operable members, a switch common to two signal-circuits and adapted to be operated by each of the operable members, one said signal-circuit being completed when connection is made with the line, and means for operating the operable members.

28. The combination with a telephone-line, of a relay provided with superposed armatures and associated with the line, a spring-
10 switch adapted to be operated by each armature, signal-circuits adapted to be controlled by the spring-switch, one signal-circuit being completed when connection is made with the line, and means for operating the armatures,
15 substantially as described.

29. An electrically - operable device nor-

mally associated with a telephone-line at a central station, and provided with operable members, a signal-controlling means adapted to be operated by the operable members, suitable signals adapted to be controlled by said signal-controlling means, and means for operating the operable members, separately or together, to operate the signal - controlling means.

In witness whereof I hereunto subscribe my name this 12th day of December, A. D. 1903.
